United States Patent Office

Des. 209,000
Patented Oct. 24, 1967

209,000

COVERED COOKING POT

Masaru Yamazaki, 1123 Furue, Furuta-machi,
Hiroshima Prefecture, Hiroshima, Japan

Filed June 13, 1966, Ser. No. 2,657

Claims priority, application Japan Apr. 20, 1966

Term of patent 14 years

(Ci. D44—1)

FIG. 1 is a side elevational view of a covered cooking pot showing my new design;

FIG. 2 is a top plan view;

FIG. 3 is a side view taken from the left of FIG. 1;

FIG. 4 is a side view taken from the right of FIG. 1; and

FIG. 5 is a bottom plan view.

I claim:

The ornamental design for a covered cooking pot, as shown.
